UNITED STATES PATENT OFFICE.

PAUL J. SCHRADER, OF CHICAGO, ILLINOIS.

TOY.

1,288,226.

Specification of Letters Patent.

Patented Dec. 17, 1918.

Application filed December 13, 1916. Serial No. 136,588.

To all whom it may concern:

Be it known that I, PAUL J. SCHRADER, a citizen of the United States, residing at Chicago, in the county of Cook and State of Illinois, have invented a certain new and useful Improvement in Toys, of which the following is a specification.

My invention relates to children's toys particularly of the type wherein various 10 separate elements are provided, some of one kind and some of another, designed to be detachably assembled to form various structures. In other words, the invention relates to toys by means of which built up structures 15 may be produced. This toy comprises rods, preferably of rectangular cross-section, and elements for connecting them together at the ends so as to hold them either in alinement or at right angles to each other, 20 or at intermediate angles, as may be desired by the builder. The object of my invention is: first to obtain simply constructed means whereby the parts may be held in assembled 25 relation; second, to provide connecting means which shall not rapidly deteriorate through use; third, to provide connections such that the assembled structure shall possess great rigidity and strength and offer 30 high resistance to breakage when pressure is exerted in any or every direction; fourth, to provide a construction such that the toy when disassembled may be closely packed and occupy but small compass, offering few, if any, interstitial spaces; fifth, to provide 35 a toy having connecting elements which may be stamped from sheet material, such as metal or fiber; sixth, to provide a connecting element readily lending itself to manufacture by comparatively simple dies; and 40 seventh, to provide a construction in which the rods may be produced entirely by sawing in distinction to turning.

I accomplish my objects by the construction illustrated in the accompanying drawings, in which:

Figure 1 is a view showing an assembled structure formed from a few of the toy elements.

Fig. 2 is a perspective view showing various elements, some of which are separated from the others to better illustrate the construction.

Fig. 3 is a perspective view showing the end of one of the rods and one form of connecting member.

Similar numerals refer to similar parts throughout the several views.

The rods are of various lengths and for the purpose of illustration I have shown rods 1, 2 and 3 of three different lengths, the rods 1 being the longest, rods 3 the shortest and the rods 2 of intermediate length. It will be understood, however, that in the toy as ordinarily manufactured there will be a greater variety of lengths and a larger number of rods of each length. In the instance illustrated, the rods 2 and 3 are so proportioned in length that when assembled, the rod 2 will form the hypotenuse of a right angle triangle of which the rod 3 forms the remaining two sides.

By preference, the rods are of constant cross-section from end to end and rectangular in cross-section. At the ends, the rods have transverse slots 4 and 5 as best shown 75 in Fig. 3. By preference, these slots are at right angles to each other and parallel respectively to the edges and sides of the rod. In the best form, the bottoms of these slots are squared to form abutments or seats for 80 the inserted edges of the connecting elements presently to be described.

In the form selected to illustrate the invention, the main connecting members consist of plates 6 formed of sheet material, 85 preferably fiber or thin gage metal. In the best design these plates are polygonal in outline. In the present case they are octagonal. Said plates are provided with fins 7 arranged at right angle to the plates and in the 90 form here illustrated, said fins consist of separate pieces, as best shown in Fig. 2. The fins have slots 8 wide enough to snugly receive the plate and the plate has a number of slots 9 which snugly receive the fins. 95 Hence when the plates and fins are assembled they give the effect of constituting a single piece in so far as their function as connectors is concerned. In the best design, the slots 9 extend radially from the middle 100 point of each side of the polygon, hence in the present instance there are eight of these slots in each plate and they lie at an angle of forty-five degrees apart. By preference, the width of the slots and the gage of the 105 sheet material are so proportioned that the fin may be detached from the plate by exerting a moderate force by the thumb and finger, but in any event, the tendency of the parts is to stay assembled.

The plates 6 and their fins 7 may be considered as the main connecting members because they are capable of forming centers from which radiate a number of different 5 rods. By arranging the rods with their greatest width transversely placed (as shown in the upper portion of Fig. 1) as many as eight rods may be connected to a single plate, and when thus connected their 10 corners will be tangent, as indicated. By arranging the rods flatwise, as shown at the lower portion of Fig. 1, instead of edge-wise, as shown at the upper portion of the figure, only four rods may be accommodated 15 and their corners will then be tangent, as indicated at the bottom of Fig. 1. This forms a source of strength as part of the sidewise strain will be taken up by companion rods.

20 I have made provision for also attaching two rods end to end in alinement with each other. The means for accomplishing this is shown in the lower portion of Fig. 3, wherein I have shown two rectangular elements 25 10, 11, forming a member which I will refer to as a "cross." The constituent elements of this cross are of sheet material of the same substance and thickness as plates 6 and fins 7, but of twice the length of the fins 7. 30 Hence, they fit snugly into the slotted ends 35 of the rods and when thus assembled hold two rods in alinement. By preference the elements 10 and 11 are counter slotted for assembly and can be separated by applying a moderate force to them.

In operation, the user commences with the 40 parts disassembled and then proceeds to build up a structure by selecting the various elements as fancy dictates and assembling 45 them in the manner which will be apparent from the foregoing description. On account of the shape of the parts a great variety of structures may be produced and these will simulate mechanical and architectural structures, thus lending special interest. And

these structures will possess rigidity and strength greater than might be expected from mere inspection. As the connecting members, both main and secondary, comprise elements whose planes are arranged 50 at right angles to each other, a high resistance to breakage is offered regardless of the direction of strain. The structure is fortified against strain in any direction. Furthermore, the individual parts are easy to 55 assemble and are but slightly susceptible to wear, for no compression need be exerted upon the wooden members (of which substance the rods are preferably composed) because said wooden members fit over and 60 receive the connecting members. The toy is also simple to manufacture, the ends of the rods simply being slotted, which can be done by sawing, while the plates may be readily punched. When the parts are all separated 65 they may be stowed away in a relatively small container for the reason that the rods, being of rectangular cross-section, may be laid surface to surface without producing any interstitial spaces, while the connecting 70 elements, being of sheet metal, may also be made to occupy a comparatively small space.

Having thus described my invention, what I claim as new and desire to secure by Letters Patent, is:

75

A built-up toy, comprising a plurality of rods each having an end provided with slots intersecting each other at right angles, a continuously flat connecting element engaged in one series of corresponding slots of the 80 bars, transverse fins carried by the connecting element and engaged respectively in the other series of slots, the fins being so positioned on the element that when the rods are secured at adjacent points on the element the ends of said rods are engaged and brace the resulting structure.

85

In witness whereof, I have hereunto subscribed my name.

PAUL J. SCHRAADER.
